UNITED STATES PATENT OFFICE.

WILLIAM McCABE, OF NEW YORK, N. Y.

CORSET-CLASP.

SPECIFICATION forming part of Letters Patent No. 225,849, dated March 23, 1880.

Application filed January 10, 1880.

To all whom it may concern:

Be it known that I, WILLIAM McCABE, of the city, county, and State of New York, have invented a new and useful Improvement in Corset-Steel Fastenings, of which the following is a specification.

Figure 1 is a front view of my improvement, and Fig. 2 is a sectional view taken through line $x x$, Fig. 1.

10 The object of this invention is to prevent the accidental separation of corset-fastenings.

The invention consists in forming the hook-plate with a spring-tongue, as hereinafter shown and described, to prevent the accidental separation of the hooks and eyes after they have been fastened.

15 A B represent the steels of a corset, which are made in the usual way. To one of the steels, as B, is attached a plate, C, upon the forward end of which is formed a hook, D, to hook into the eye E of a plate, F, attached to the other steel, A. The hook-plate C has an offset formed in it to receive the cloth of the corset.

20 In the body of the plate C is cut out a strip or tongue, G, which is bent outward, so that its free end may rest against the inner side of the hook D to prevent the said hook from be-

coming accidentally unhooked. The hook C 30 D and the spring G may be made in one piece, as shown in the drawings, or separate, as may be desired. I prefer to make them in one piece, as being less expensive in manufacture.

With this construction, should the steels A 35 B be pressed together the edge of the eye-plate F will pass in beneath the spring G, and be thus prevented from becoming unhooked.

I am aware of Patent No. 187,308 on corset- 40 fastener; but in this the tooth is liable to come out of the eye or hole whenever the steels are pressed together by the bending of the body, which objection my construction is intended to provide against.

45

What I claim as new is—

A hook-and-eye corset-fastening formed of two plates, C F, in one of which is cut an aperture, E, the other being bent at the end into a hook, D, and cut to form a tongue, G, all 50 arranged to operate as shown and described.

WILLIAM McCABE.
